(57) **CLAIM**

The ornamental design for an ice tray for cup, as shown and described.

DESCRIPTION

FIG. 1 is a front, bottom perspective view of an ice tray for cup, shown in a fully assembled configuration, showing my new design;

FIG. 2 is a rear, top perspective view thereof;

FIG. 3 is an exploded view of the ice tray for cup;

FIG. 4 is another exploded perspective view of the ice tray for cup, shown in an environment of use;

FIG. 5 is a front, bottom perspective view of a first element of the ice tray for cup;

FIG. 6 is a rear, top perspective view thereof;

FIG. 7 is a front elevation view thereof;

FIG. 8 is a rear elevation view thereof;

FIG. 9 is a left side elevation view thereof;

FIG. 10 is a right side elevation view thereof;

FIG. 11 is a top plan view thereof;

FIG. 12 is a bottom plan view thereof;

FIG. 13 is a front, bottom perspective view of a second element of the ice tray for cup;

FIG. 14 is a rear, top perspective view thereof;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a top plan view thereof; and,

FIG. 20 is a bottom plan view thereof.

The broken lines are shown for the purpose of illustrating both parts of the ice tray for cup as well as environmental subject matter. None of the broken lines form part of the claimed design.

1 Claim, 20 Drawing Sheets
